UNITED STATES PATENT OFFICE.

SPENCER C. CARY, OF BROOKLYN, NEW YORK, ASSIGNOR TO WILLIAM H. CARY, OF SAME PLACE.

DESIGN FOR A CLOTHES-HOOK.

SPECIFICATION forming part of Design No. 11,889, dated July 27, 1880.

Application filed April 5, 1880. Term of patent 14 years.

To all whom it may concern:

Be it known that I, SPENCER C. CARY, of the city of Brooklyn, county of Kings, and State of New York, have originated and designed a new and original shape of a nail designed for use as a clothes-hook and other uses, of which the following is a full, clear, and exact description, reference being had to the accompanying illustrations, making part of this specification.

Figure 1 shows the configuration of the hook; Fig. 2, the configuration of the end bar.

C represents the body part of my design, which I term the "sleeve." This sleeve is of the configuration shown in the drawings, having the sides *d* and the bell-shaped projection, forming the shoulder *f*, on one end of said sleeve. To the end opposite this bell-shaped end, and held in place to the sleeve C by the head of a screw, is the bar B, which is of the shape of a parallelogram having rounded cor-

ners. In this bar B, at its center, may be formed a recess or depression, wherein the eye of the screw holding the said bar attached to the sleeve may be pressed.

Around the bar B, and in the depression where the head of the screw clasps said bar, may be placed a piece of metal or a rim of metal. This rim or piece of metal may be decorated or engraved, if so desired.

What I claim as my invention is—

A design for a clothes-hook or other similar article in which the body or sleeve is bell-shaped and its end bar in the form of a parallelogram having rounded ends, all substantially as shown and described.

Witness my hand this 2d day of April, 1880.

SPENCER C. CARY.
